GAS LIFT PUMP FOR OIL WELLS

George R. Cole, Glendale, Calif.

Application April 11, 1949, Serial No. 86,700

4 Claims. (Cl. 103—260)

1

This invention relates to an improved liquid pump for oil wells.

An object of this invention is to provide a pump structure adapted to be inserted in a well casing for lifting the oil entering the casing, the pump operating in cycles according to the rate of flow of the oil into the casing.

Another object of this invention is to provide a pump structure wherein the gas used to lift the oil will be intimately mixed with the oil whereby the grade of the oil will be improved.

A further object of this invention is to provide an improved method or process of lifting oil from a well which will operate automatically from pressure at the top of the well.

A further object of this invention is to provide a well pump of this kind which will operate in any depth of well, and with gas pressure existing at the top of the well, the device will operate continuously in cycles.

A further object of this invention is to provide a gas lift pump having a main or high pressure gas controlling valve, and a secondary or low pressure valve, with the latter functioning after the main valve has been closed, and with pressure existing in the lift chamber, designed to exhaust the liquid from the lift chamber in addition to producing a relatively low pressure therein so that the liquid may freely rise in the intake tube. When the pressure in the lift chamber drops to a predetermined degree, the secondary valve will automatically close and will remain closed until pressure again rises in the lift chamber after opening of the main valve.

With the above and other objects in view, my invention consists in the arrangement, combination and details of construction disclosed in the drawings and specification, and then more particularly pointed out in the appended claims.

In the drawings,

Figure 1 is a detail side elevation, partly in longitudinal section, of a gas lifting pump constructed according to an embodiment of this invention.

Figure 2 is a fragmentary longitudinal section of the upper portion of the pump on an enlarged scale and taken on the line 2—2 of Figure 3.

Figure 3 is a sectional view taken on the line 3—3 of Figure 2.

Figure 4 is a fragmentary plan view, partly in section, showing the manner of securing the top wall to the outer housing.

Figure 5 is a fragmentary vertical section taken on the line 5—5 of Figure 4.

Figure 6 is a fragmentary sectional view taken on the line 6—6 of Figure 2.

Referring to the drawings, the numeral 10 designates generally a tubular housing which is adapted to be extended into a well casing and may be of sufficient length so that at least the lower portion thereof will be disposed within the liquid such as oil which is positioned in the bottom of the well.

The housing 10 includes a cylindrical side wall 11, and a bottom wall 12 formed with an upstanding nipple 13 in the center thereof, within which an upwardly or inwardly opening ball check valve 14 is mounted.

A strainer or screen 15 extends downwardly from the bottom wall 12 and is adapted to screen the liquid entering through the intake nipple 13. The housing 10 includes a top wall 16 which is secured by means of a plurality of washers 17 engageable in recesses 18 formed in the side wall 11. The washers 17 are tightly held in position by means of bolts 19 which are threaded into bosses 20 carried by the cylindrical side wall 21 of an inner housing generally designated as 22.

The inner housing 22 includes a bottom wall 23 and a top wall 24 through which the bolts 19 are adapted to extend, and a sealing gasket 25 is interposed between the outer top wall 16 and the wall 24.

A pressure pipe 26 is extended through the two top walls 16 and 24 and is adapted to be connected to a suitable source of pressure supply such as gas pressure for maintaining a predetermined pressure of gas within the outer pressure chamber 27 which is formed within the inner housing 22.

The bottom wall 23 is formed with an outlet port 28 and with a valve seat 29 on which a valve 30 is adapted to engage, being constantly urged toward the seat 29 by means of a spring 31. The upper end of the spring 31 engages a substantially triangular plate 32 which bears at its upper side against a pair of lugs 33 carried by the inner side of the side wall 21 and also bears against a lug 34 which is carried by an upwardly tapering body 35 which extends from the bottom wall 23 and forms a mixing chamber 36.

A discharge or outlet pipe 37 is threaded into the upper end of the body 35 and is adapted to be connected to a separator wherein the liquid is separated from the gas. The bottom wall 23 has engaging thereagainst an intermediate plate 38 which is formed with an opening 39 aligning with the opening 28. The plate 38 is provided centrally thereof with a chamber 40 communicating with the opening 39 through one or more downwardly inclined passages 41.

The bottom wall 23 is provided with a plurality of openings 42 which communicate chamber 40 with mixing chamber 36. The plate 38 comprises the nozzle carrying or supporting plate and a plurality of nozzles 43 are threaded into the plate 38, projecting upwardly through the chamber 40 and loosely projecting through the openings 42. A lower plate or body 44 is secured to the intermediate plate 38 and is provided with a chamber 45 communicating with opening or chamber 39 and the passages 41 also communicate with chamber 45.

The lower plate 44 is provided centrally thereof with a relatively large downwardly tapering opening or chamber 46, and the upper end of a

suction pipe 47 is threaded into a nipple or boss 48 and opens into the suction chamber 46. A ball check valve 49 is adapted to seat on the upper end of the pipe 47 when in closed position and when in open position is adapted to bear against an upwardly offset part 50 which is formed in the intermediate plate 38.

The valve 30 includes a depending valve stem 51 which extends through the lower plate 44 and engages a valve lifting lever 52 which is rockably carried by a pivot 53 extending through a pair of depending ears 54 extending downwardly from the plate 44. The lifting lever 52 is formed with a ring-shaped intermediate part 55 loosely engaging about the pipe 47 and the boss 48. The lifting lever 52 is formed in the lower side thereof with an arcuate seat 56 within which a roller 57 carried by one arm 58 of a bellcrank lever 59 is adapted to engage. When the roller 57 is engaged in the seat or recess 56, lifting lever 52 will be in the valve opening position shown in Figure 2.

The bellcrank 59 is rockably mounted on a pivot 60 extending through a pair of ears 61a depending from the plate 44 oppositely from the ears 54. The bellcrank lever 59 is formed with a pair of longitudinally curved arms 61 which straddle the suction pipe 47, and a roller 62 is mounted between the arms 61 on a pivot 63.

A vertically movable valve operating float 64 is slidably disposed about the suction pipe 47 and when the float 64 is in its uppermost position the top wall 65 of the float will engage roller 62 so as to raise the curved arms 61 upwardly and raise arm 58 to substantially a vertical position and thereby upwardly rock valve lifting lever 52 to a valve opening position.

As shown in Figure 2, the arms 61 are formed with downwardly inclined extensions 66 between which the roller 62 is rotatably mounted. The suction pipe 47, as shown in Figure 1, terminates at a point slightly above the intake nipple 13 for the outer housing 10 and a valve releasing lever 67 is rockably mounted at the lower end portion of the suction pipe 47, being mounted on a pivot 68 and provided with an upwardly extending arm 69 on which a roller 70 is rotatably mounted.

The lever 67 is connected with lever 59 by means of an elongated rod 71 which has a degree of flexibility and the upper end of rod 71 is mounted on a pin 72 carried by a pair of obtusely disposed arms 73 which extend from the upper portions of the extensions 66. The rod 71 extends over a pin or bar 74 which extends between the arms 73 so that rod 71 will be flexed to the desired degree in order to hold this rod out of contact with float 64 when the latter is in substantially its uppermost valve opening position.

The provision of the lower valve releasing lever 67 assures the maintaining of valve 30 in an open position until the housing 10 has been substantially exhausted of liquid. Furthermore, by providing the recess 56 in lifting lever 52, the bellcrank 59 is held against downward rocking to valve releasing or closing position until lever 59 is positively rocked downward by engagement of float 64 with the releasing lever 67.

In order to provide for exhausting of the liquid in mixing chamber 36 after valve 30 has been moved to closed position, I have provided an auxiliary valve 75 which is adapted to engage when in closed position on a valve seat 76 formed in the intermediate plate 38. The bottom wall 23 is formed with a plurality of passages 77 communicating high pressure chamber 27 with chamber 78 formed in plate 38 above the valve seat

76. The plate 38 is formed with a lateral passage 79 communicating with valve seat 76 and with a vertical passage 80 which communicates with a similar vertical passage 81 formed in the lower plate 44.

A low pressure nozzle 82 is threaded into the lower plate 44, being inclined upwardly and inwardly for regulating the discharge of gas into chamber 40 after valve 30 has been closed. An exhaust passage 83 is formed in the plate 44, communicating with the nozzle passage 84 formed in plate 44 so that the gas or fluid pressure in outer housing 10 may be exhausted upwardly into chamber 36 when both valves 30 and 75 are in closed position.

Valve 75 is secured to a flexible diaphragm 85 mounted in a valve housing 86 and diaphragm 85 is constantly urged downwardly by means of a spring 87 which abuts at its upper end against a spring adjusting screw 88 threaded through a perforate wall 89 carried by a cap 90. The cap 90 is threaded through the walls 16 and 24 and the cap 90 at its upper end communicates with the atmosphere so that there will always be present atmospheric pressure on the upper side of diaphragm 85.

A pressure chamber 91 is formed in housing 86 below diaphragm 85 and chamber 91 communicates with mixing chamber 36 through at least one passage 92. The passage 92 will communicate the higher pressure in mixing chamber 36 with chamber 91 so that diaphragm 85 will be flexed upwardly to valve opening position when valve 30 is open.

In the use and operation of this device, the housing 10 is extended downwardly into the well casing. The extension of the housing into the well casing is of such degree that when the float 64 is in its uppermost position the float will be at substantially the upper level of the liquid such as oil which is disposed within the well. The liquid entering the housing 10 will open check valve 14 and will raise float 64 to the uppermost position of the float wherein bellcrank 59 will be rocked upwardly and valve 30 will be moved upwardly to open position by upward rocking of lifting lever 52.

When bellcrank lever 59 is in its valve opening position this lever is locked in the valve opening position by engagement of roller 57 in recess 56. With valve 30 in open position the higher gas pressure in pressure chamber 27 will be communicated to chamber 40 in intermediate plate 38 and this gas pressure will flow upwardly through the openings 42 about the upper ends of nozzles 43. The liquid which is in housing 10 will also be in pipe 47 and when the gas passes the upper ends of nozzles 43 a partial vacuum or suction will be created in suction chamber 46 raising valve 49 to open position. The liquid will then pass upwardly through nozzles 43 and this liquid will be mixed with the gas which is rising upwardly in mixing chamber 36. At the time the gas is entering mixing chamber 36 a high pressure is produced in chamber 36 which moves upwardly and this pressure will be communicated to diaphragm chamber 91 through passage 92. High pressure in chamber 91 will raise diaphragm 85 upwardly so that auxiliary valve 75 will be moved to an open position.

At the time valve 30 is in open position the opening of valve 75 will have little effect on the lifting of the liquid. However, when float 64 is lowered by exhausting of liquid in housing 10, and when float 64 strikes valve releasing lever 67,

valve 39 will be closed. At this time there will remain sufficient pressure in mixing chamber 36 and in diaphragm chamber 91 to hold valve 75 in open position.

Gas will be discharged through jet or nozzle 82 into chamber 40 and this gas passing upwardly through the openings 42 will serve as an exhausting means for exhausting the final liquid which exists in mixing chamber 36. When the pressure in mixing chamber 36 drops to a predetermined degree, spring 87 will move diaphragm 85 downwardly and valve 75 will be moved to a closed position.

It will be understood that valve 75 may remain open for a substantial period after closing of valve 39 during which time float 64 may be again moving upwardly by reason of liquid entering the lower portion of housing 10. When valve 75 is in its closed position the gas in the upper portion of housing 10 below plate 44 will be exhausted through exhaust port 83, nozzle chamber 84 and pressure chamber 40.

I do not mean to confine myself to the exact details of construction herein disclosed, but claim all variations falling within the purview of the appended claims.

What I claim is:

1. A gas lift pump comprising a housing adapted to be disposed in the lower portion of a well, a valved intake in the lower end of said housing, suction means in the upper portion of said housing, and float operated means in said housing correlated with said suction means for rendering the latter operative when said housing is substantially filled with liquid, said float operated means including a spring-pressed valve, a valve opening lever, a bellcrank rockably carried by said housing engaging said lever, and a vertically movable float engageable in the uppermost position thereof with said bellcrank to move said valve to open position, a valve releasing lever rockably disposed in the lower portion of said housing and engageable by said float when the latter is in a lower position, correlated means carried by said lever and said bellcrank for holding said lever in valve opening position when said float moves downwardly, a connection between said releasing lever and said bellcrank to rock the latter to valve closing position at the time said float is in its lower position, and a discharge outlet for said pump.

2. A gas lift pump comprising a housing adapted to be disposed in the lower portion of a well, a high pressure chamber in the upper portion of said housing, a mixing chamber centrally of said high pressure chamber, an intermediate pressure chamber communicating with said high pressure and mixing chambers, a suction chamber below said intermediate chamber, a plurality of partition means separating said chambers, suction nozzles communicating said suction chamber with said mixing chamber for vaporizing the fluid admitted to said mixing chamber, a spring-pressed valve normally cutting off communication between said high and intermediate pressure chambers, means forming a passage connecting said high pressure and mixing chambers, a normally closed second valve in said passage, a second pressure chamber communicating with said mixing chamber, a diaphragm operator secured to said second valve, said means forming the passage extends through the partition means between said high pressure and mixing chambers, float operated means in said housing engageable with said first valve for moving the latter to open

position when said housing is substantially filled with liquid, and a discharge outlet for said pump.

3. A gas lift pump comprising a housing adapted to be disposed in the lower portion of a well, a high pressure chamber in the upper portion of said housing, a mixing chamber centrally of said high pressure chamber, an intermediate pressure chamber communicating with said high pressure and mixing chambers, a suction chamber below said intermediate chambers, a plurality of partition means separating said chambers, suction nozzles communicating said suction chamber with said mixing chamber for vaporizing the fluid admitted to said mixing chamber, a spring-pressed valve normally cutting off communication between said high and intermediate pressure chambers, means forming a passage connecting said high pressure and mixing chambers, a normally closed second valve in said passage, a second pressure chamber communicating with said mixing chamber, a diaphragm operator secured to said second valve, said means forming the passage extends through the partition means between said high pressure and mixing chambers, float operated means in said housing engageable with said first valve for moving the latter to open position when said housing is substantially filled with liquid, said float operated means including means for holding said first valve in open position until said housing is substantially emptied of liquid, and a discharge outlet for said pump.

4. A gas lift pump comprising a housing adapted to be disposed in the lower portion of a well, a valved intake in the lower end of said housing, suction means in the upper portion of said housing, a spring-pressed regulating valve for said suction means including a stem projecting below said suction means, a valve operating lever rockably carried by the lower end of said suction means and including a keeper recess in the lower side thereof, a bellcrank rockably carried by said suction means and including a substantially horizontal side and an upwardly projecting side, the terminal upper end of said latter side being engageable in said keeper when said housing is substantially full, a float in said housing engageable with said bellcrank when said housing is substantially full to thereby rock said bellcrank and lever upwardly to valve opening position, a release lever rockably disposed in the lower portion of said housing, a connection between said bellcrank and said release lever whereby downward rocking of said release lever by said float when said housing is substantially empty will release said first named lever from said bellcrank and thereby effect cutting off of said suction means, and a discharge outlet for said pump.
